E. G. BUSSE.
LUBRICATED SIDE BEARING.
APPLICATION FILED FEB. 27, 1922.

Patented Nov. 14, 1922.

Inventor
Edwin G. Busse
By *F. R. Cornwalt* Atty

UNITED STATES PATENT OFFICE.

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

LUBRICATED SIDE BEARING.

Application filed February 27, 1922. Serial No. 539,478.

To all whom it may concern:

Be it known that I, EDWIN G. BUSSE, a citizen of the United States, residing at the city of Chicago, county of Cook, and State 5 of Illinois, have invented a certain new and useful Improvement in Lubricated Side Bearings, of which the following is a full, clear, and exact description, such as will enable others skilled in the art to which it applies 10 to make and use the same, reference being had to the accompanying drawings, forming part of this application, in which,—

Figure 1 is a vertical sectional view of my 15 improved lubricated side bearing.

Fig. 2 shows a section and an end view of a modified form.

Figure 3 is a side elevational view partly 20 in vertical section of another modified form.

Figure 4 is a bottom plan view of the form shown in Figure 3.

This invention relates to a new and useful improvement in lubricated side bearings, being designed particularly for use in connection 25 with top side bearings, i. e., those which are secured to the underframing of the car body, although my improvements may be used in the lower side bearing, i. e., that one which is carried by the car truck 30 or its bolster. However, when used in connection with an upper side bearing, the gravity feed materially assists in the lubrication.

In the drawings, 1 indicates a base plate of a side bearing, in this instance constituting 35 the top wall from which depends side walls 2 and a bottom wall 3, the latter being provided with a series of openings or perforations 3^a, as shown.

4 indicates a bore on the upper portion 40 of the bearing, said bore having a port 4^a at one end leading into a chamber 5, which latter is in communication with the ports 3^a.

A plug 6 of the same or slightly larger diameter than the bore 4 is threadedly mounted 45 in an opening in one of the side walls in alignment with the bore 4 through which opening a reaming or finishing tool for the bore 4 may be inserted for well-understood purposes.

50 7 indicates a piston head mounted on the inner end of a rod 8 having threaded engagement with an opening in one of the

side walls of the bearing, said rod 8 having a handle 9 upon its outer end by which it may be turned and the piston 7 forced inwardly in its bore.

In operation, waste is inserted into the chamber 5, after which the bore in chamber 5 is filled with grease or other lubricant. The piston head 7 should be in its outermost 60 position at the time. The plug 6 is now inserted and the grease or lubricant will feed by capillary attraction, assisted by gravity, through the ports 3^a, when the device is first loaded. When the lower surface of the 65 bearing becomes dry, or the lubricant is no longer self-feeding, as above indicated, the rod 8 can be rotated, forcing the piston head 7 inwardly, this action constituting a forced feed, whereby the lubricant is compelled to 70 pass through openings or ports 3^a by pressure. The handle 9 can be turned from time to time as lubricant is required until its movement is arrested, after which the bearing 75 will have to be recharged with lubricant.

In Figure 2, I have shown a similar construction except that the plug 6 has been omitted and a packing nut 10 is used at the end of the bore.

In Figures 3 and 4, I have shown another 80 form in which I have provided an overflow and compression chamber 11 in the upper portion of the bearing. In this form, as in Figure 2, the packing nut 10 and its carried piston and piston rod may be removed for 85 the purpose of inserting waste in the chamber 5 and charging the bearing with the lubricant. The chamber 5 communicates with the chamber 11 by means of an opening 12. When first charged the chamber 11 may be 90 filled with lubricant, and as this seeps through the waste to the ports 3^a, the piston may be forced inwardly so as to exert a pressure on the lubricant, and at the same time place any air which may be trapped in chamber 11 under pressure, which air pressure 95 will be constantly exerted upon the surface of the oil until it becomes exhausted, after which the piston may be moved further inwardly.

100 While I have shown my improved lubricating device as adapted to side bearings for railway cars, it is obvious that this same principle can be employed in connection

with third or fourth point supports for brake beams; and, also, that waste need not be employed, unless desired.

What I claim is:

- 5 1. A lubricated bearing comprising a housing having an apertured contact wall on one side, said housing being provided with a horizontally disposed bore and a horizontally disposed lubricant chamber super-
0 posed in relation to, and in communication with each other, a piston in said bore, and means for operating said piston.
2. A lubricated bearing comprising a housing having an apertured contact wall, said housing being provided with a horizontally disposed lubricant chamber and a horizontally disposed cylindrical bore super-

posed in relation to, and in communication with each other, a piston in said bore, and removable means in the housing for giving 20 access to the lubricant chamber through said piston bore.

3. A lubricated bearing comprising a housing, an apertured contact wall on one side of said housing, said housing having a 25 bore, a lubricant chamber and an overflow chamber all in communication with each other, a piston in said bore, means for operating said piston, and removable means arranged in the housing for giving access to 30 said piston and said lubricant chamber.

In testimony whereof I hereunto affix my signature this 17th day of February, 1922.

EDWIN G. BUSSE.
